DESIGN FOR A GLOVE

Wallace E. Meyers, New York, N. Y.

Application August 29, 1936, Serial No. 64,637

Term of patent 7 years

To all whom it may concern:

Be it known that I, Wallace E. Meyers, a citizen of the United States of America, residing in Manhattan, county of New York and State of New York, have invented a new, original, and ornamental Design for a Glove, of which the following is a specification, reference being had to the accompanying drawing, forming part thereof, wherein,

The glove is characterized by an ornamentation adjacent to the edge of the cuff, comprising close continuous lacings, as shown.

I claim:

The ornamental design for a glove, substantially as shown and described.

WALLACE E. MEYERS.
